J. OLIPHANT

AIR LIFT PUMP

Original Filed July 29, 1919

Inventor:
John Oliphant
race - 1000

UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

AIR-LIFT PUMP.

Application filed July 29, 1919, Serial No. 313,997. Renewed February 11, 1924.

To all whom it may concern:

Be it known that I, JOHN OLIPHANT, a citizen of the United States, residing at Chicago, in the county of Cook and State of Illinois, have invented certain new and useful Improvements in Air-Lift Pumps, of which the following is a full, clear, and exact specification.

My invention relates to air lift pumps.

It has for its object to provide an improved air lift pump. A further object of my invention is to provide an improved air lift pump of the general type described and claimed in the Nelson Patent 1,151,529, wherein the controlling means are entirely automatic in their action and are adapted to produce a more perfect emulsion despite variations of pressure and with greater efficiency and facility. In practice with the ordinary form of foot piece the air and water pressures just outside of the mixing tube are nearly balanced, but it has been found that when pumping under certain conditions a distinct improvement in the steadiness of discharge and reduction in air consumption and a better emulsification are secured by carrying an air pressure in the mixing tube slightly in excess of the submergence requirements, thus forcing the air into the ascending column of water at a higher velocity. To provide means for accomplishing this improved mode of operation is, more specifically, the object of my invention.

In the accompanying drawings I have shown for purposes of illustration one embodiment which my invention may assume in practice.

In these drawings,—

Fig. 1 is a side elevation of an air lift system equipped with my improvement.

Fig. 2 is a detail vertical sectional view of the pump.

Fig. 3 is a transverse sectional view on line 3—3 of Fig. 2.

In this illustrative construction I have shown an air lift system comprising the usual compressor 1 supplying a receiver 2, which in turn discharges into a down pipe 3 leading to an air lift pump 4 of an improved construction hereinafter described, located in the well casing 5, the pump discharging the mixture of air and liquid formed thereby through an up-pipe 6 into a communicating discharge line 7.

In my improved construction it will be observed that the down-pipe 3 communicates through an elbow 8 with a threaded sleeve 9 on the lower end of a hollow upstanding mixing member 10. As shown, this member 10 is also disposed coaxially with and within a pump casing 11 threaded between an elbow carrying member 12 and the up-pipe 6 and having a reduced or venturi portion 13 at its upper end. It will here also be observed that the member 10 is provided with oblique apertures or perforations 14 in the lower part thereof, the perforated portion herein being shown as extending from the sleeve 9 to a point within the upper half of the member 10. In a preferred form of my invention, these openings 14 are bell-mouthed as described and claimed in my co-pending application Serial No. 177,605, filed June 29, 1917, which has, since the filing of this application, matured into Letters Patent No. 1,363,198, dated Dec. 21, 1920, but for the purposes of the present invention and to facilitate illustration thereof herein, this feature has not been shown in the drawings. It will also be noted that movable longitudinally of the member 10 and, herein, in sliding engagement with the wall of the axial opening 15 therein, is a perforation covering member, herein in the form of an elongated plunger 16, having at its lower end a conical portion 17 adapted to seat in a corresponding seat 18 formed on the inner end of the sleeve 9 and having at its upper end an axially disposed, upwardly extending rod 19 slidable in a cap member 20 on the upper end of the member 10. In my improved construction it will also be observed that this rod 19 is relatively short, the weight of the parts being such that the plunger 16 normally tends to seat on the seat 18 and close all the perforations 14, and that the plunger and its rod unite to form a weighted controlling member normally opposing flow of pressure fluid into the member 10 and adapted to float or ride on the crest of the incoming stream of pressure fluid, and by thereby increasing the minimum pressure at which the latter may discharge and so the velocity of the latter, and by causing it to pass through a proper number of perforations, cause the pressure fluid to form a more perfect emulsion.

In the use of my improved construction

it will be observed that all necessity for connecting the plunger with any controlling mechanism at ground level is entirely eliminated, the controlling mechanism instead 5 operating automatically below ground at all times, regardless of the attention or inattention of the operator, to maintain the pump at its maximum efficiency regardless of variation in pressure fluid flow thereto, the 10 same when the volume of air supply decreases, automatically decreasing or cutting off the flow through the pump so as to maintain the pressure or velocity through the open orifices, and when the volume of 15 air supplied increases, automatically increasing the flow area by opening more orifices, and during full flow conditions assuming an inoperative condition in the unperforated upper end of the foot piece. It 20 will also be observed that at the same time that the effectiveness of the controlling mechanism is thus augmented and rendered certain at all times without requiring any attention on the part of the operator, 25 through my improved construction it is made possible to simplify the equipment by eliminating the long length of rod extending from the pump to the surface of the ground, and all controlling or adjusting 30 means for such a rod, and also to reduce the number of perforations required in the upper end of the member 10. These and other advantages of my improved construction will, however, be clearly apparent to those 35 skilled in the art.

While I have in this application specifically described one embodiment which my invention may assume in practice, it will be understood that this form of the same is 40 shown for purposes of illustration and that the invention may be modified and embodied in various other forms without departing from its spirit or the scope of the appended claims.

45 What I claim as new and desire to secure by Letters Patent is:

1. In an air lift pump, a perforated mixing tube, and floating means thereon adapted automatically to permit an increase in 50 the rate of pressure fluid flow through the perforations therein.

2. In an air lift pump, a perforated mixing tube, and automatically operative floating means associated therewith for causing, 55 so long as pumping takes place, a velocity of flow through the individual perforations in the mixing tube in excess of that which would result from a pressure sufficient to effect discharge against the existing head.

60 3. In an air lift pump, a perforated mixing tube, and a floating member movable relative thereto and over the perforations therein responsive to variations in fluid pressure supply to said mixing tube.

65 4. In an air lift pump, a perforated hol-

low mixing tube and a plunger guided therein and movable over the perforations therein in response to variations in pressure supply to said riser mixing tube.

5. In an air lift pump, a perforated mixing tube, and a member guided thereon and movable over the perforations therein to vary the number of effective perforations automatically in proportion to a variation in fluid pressure supply. 70

6. In an air lift pump; a perforated mixing tube, and a member guided thereby and movable longitudinally thereof in response to variations in fluid pressure supply to increase the number of effective perforations 80 as the fluid pressure increases.

7. In an air lift pump, a perforated mixing tube, and a member guided thereby and movable longitudinally thereof in response to variations in fluid pressure supply to decrease the number of effective perforations 85 as the fluid pressure decreases.

8. In an air lift pump, a mixing tube perforated throughout a portion of its length, and a member movable longitudinally thereof in response to variations in fluid pressure supply to said mixing tube and disposable during maximum fluid pressure supply opposite the unperforated portion of the latter. 95

9. In an air lift pump, a mixing tube perforated throughout a portion of its length, and a member movable longitudinally thereof in response to variations in fluid pressure supply to said mixing tube and during minimum fluid pressure supply closing the perforations in said mixing tube. 100

10. In an air lift pump, a mixing tube perforated throughout a portion of its length, and a floating plunger therein movable longitudinally thereof in response to variations in fluid pressure supply to said mixing tube and disposable in said unperforated portion. 105

11. In an air lift pump, a perforated hollow mixing tube having an axially disposed seat in its lower end and a perforated cap in its upper end, and a floating plunger adapted to rest on said seat and having a rod slidable through the perforation in said cap. 110

12. In an air lift pump, a mixing member having a plurality of discharge orifices therein, and means for automatically varying the number of active orifices in accordance with variations in the pressure supply to said mixing member. 115

13. In an air lift pump, a mixing member, air discharge means thereon, and a member movable relative to said mixing member and responsive to pressure variations therein to govern said discharge means. 120

14. In an air lift pump, a mixing member, air discharge means thereon, and a member movable relative to said mixing member and 125

130

responsive to pressure variations therein to vary the discharge area of said discharge means.

15. In an air lift pump, an air discharge member, and automatic loading means cooperating therewith and adapted to maintain the discharge pressure substantially constant for a given head.

16. In an air lift pump, a perforated mixing tube, and automatic means therein adapted to maintain the discharge pressure substantially constant for a given head.

17. In an air lift pump, an air discharge member provided with air discharge means, and loading means movable relative to said air discharge means and responsive to pressure within said air discharge member.

18. In an air lift pump, an air discharge member, and means cooperating with said air discharge member automatically necessitating, for discharge, that the pressure within the member exceed that requisite to discharge against the hydrostatic head.

19. In an air lift pump, an air discharge member, and means for automatically main-

taining, during air discharge, a predetermined difference between air pressure and hydrostatic head cooperating with said air discharge member.

20. In an air lift pump, an air discharge member, and means cooperating therewith and adapted during pumping automatically to maintain a predetermined discharge velocity for any given hydrostatic head.

21. In an air lift pump, a mixing tube perforated throughout a portion of its length, and a member movable longitudinally thereof in response to variations in pressure therein and disposable during maximum pressure opposite the unperforated portion of said mixing tube.

22. In an air lift pump, a mixing tube perforated throughout a portion of its length, and a member movable longitudinally thereof in response to variations in fluid pressure therein and during minimum fluid pressure closing the perforations in said mixing tube.

In testimony whereof I affix my signature.
JOHN OLIPHANT.

Certificate of Correction.

It is hereby certified that in Letters Patent No. 1,508,667, granted September 16, 1924, upon the application of John Oliphant, of Chicago, Illinois, for an improvement in "Air-Lift Pumps," an error appears in the printed specification requiring correction as follows: Page 2, line 69, claim 4, strike out the word "riser"; and that the said Letters Patent should be read with this correction therein that the same may conform to the record of the case in the Patent Office.

Signed and sealed this 4th day of November, A. D. 1924.

[SEAL.]

KARL FENNING,
Acting Commissioner of Patents.
